FIG. 1 is a perspective view of a light emitting device package showing our design;

FIG. 2 is a top view thereof;

FIG. 3 is a front side view thereof;

FIG. 4 is a rear side view thereof;

FIG. 5 is a right side view thereof;

FIG. 6 is a left side view thereof;

FIG. 7 is a bottom view thereof; and,

FIG. 8 is a bottom perspective view thereof.

The dash-dot broken lines define the bounds of the claimed design and form no part thereof. The dot-dot broken line showing of the light emitting device package is for the purpose of illustrating environmental structure and forms no part of the claimed design.
